UNITED STATES PATENT OFFICE.

ELEC OPPENHEIM AND THOMAS J. BURNS, OF ROCKFORD, ILLINOIS.

ELECTRIC-CIRCUIT-CONTROLLING SWITCH.

1,146,016.

Specification of Letters Patent. Patented July 13, 1915.

Application filed May 7, 1913. Serial No. 766,135.

To all whom it may concern:

Be it known that we, ELEC OPPENHEIM and THOMAS J. BURNS, citizens of the United States, residing at Rockford, in the county of Winnebago and State of Illinois, have invented new and useful Improvements in Electric-Circuit-Controlling Switches, of which the following is a specification.

This invention relates to improvements in electric circuit controlling switches and has particular application to a manually operable combination switch.

In carrying out the present invention, it is our purpose to provide a combination-electric circuit controlling switch whereby one knowing the combination may open and close the circuit with ease and convenience and by means of which an unauthorized person, or one not knowing the combination, will be unable to close the electric circuit controlled by the switch.

It is also our purpose to provide a switch of the class described which will embody a number of sets of contacts connected in series in an electric circuit so that the circuit will remain open until both sets of contacts have been moved into circuit closing positions thereby minimizing the possibility of one unacquainted with the combination closing the circuit controlled by the switch.

Furthermore, we aim to provide a switch of the type set forth wherein the various sets of contacts may be individually manipulated or operated for opening and closing the circuit and wherein the contacts will be locked automatically in open and closed positions.

With the above and other objects in view, the invention consists in the construction, combination and arrangement of parts hereinafter set forth in and falling within the scope of the claims.

In the accompanying drawings; Figure 1 is a top plan view of a combination switch constructed in accordance with the present invention, the cover of the casing of the switch being removed. Fig. 2 is a longitudinal sectional view through the casing on the line 2—2 of Fig. 1 showing parts of the switch mechanism in side elevation. Fig. 3 is a fragmentary longitudinal sectional view through the switch. Fig. 4 is a horizontal sectional view showing a part of the mechanism in top plan and the circuit controlled by the switch in diagram. Fig. 5 is a frag-

mentary top plan view of the switch, parts being broken away.

Referring now to the accompanying drawings in detail, the numeral 1 designates a casing or housing for the mechanism of the switch, such casing being composed of any suitable material and of any desired outline.

Appropriately fastened to the lower wall of the casing adjacent to the rear wall thereof is a block 2 formed with a longitudinal bore 3 opening onto the forward end thereof, while secured to the end wall of the bore 3 axially of the latter is a guide pin 4 having the free end portion thereof loosely surrounded by a collar 5 adapted for sliding movement along the pin and within the bore 3, a coiled compression spring 6 encircling the guide pin and having one end in engagement with the adjacent extremity of the collar, such spring serving to hold the collar normally projected out of the open end of the bore. Immediately in advance of the block 2 is a bearing block 7 appropriately secured to the lower wall of the casing and formed with a passage 8 coaxial with the bore 3 in the block 2, the bearing block serving to limit the outward movement of the collar 5 under the action of the spring 6 thereby preventing accidental displacement of the collar. Fixed to the block 2 at opposite sides thereof are metallic contact strips 9 having the forward ends thereof inturned and lying upon the front end of the block 2 at opposite sides of the bore 3 therein, while suitably fastened to the outer end of the collar 5 is a bridging strip 10 adapted when forced inwardly against the action of the spring 6 to bridge the contact strips 9.

Surmounting the block 2 and secured thereto in some suitable manner is a plate 13 lying in a plane parallel with that of the block and having one end thereof abutting the rear wall of the casing 1 and the opposite end overlying the forward extremity of the block 2. Upstanding from the bearing plate 13 adjacent to the rear end and centrally thereof is a pivot block 14 having its opposite ends equipped with outwardly extending pivot pins 15.

16, 17 designate levers, each fulcrumed at one end upon one of the pivot pins 15 and having the opposite end thereof terminating substantially flush with the forward extremity of the plate 13 and bifurcated or

forked as at 17. Upstanding from the upper edge of each lever is a lug 18 disposed approximately centrally of the length of the lever. Fulcrumed in the forked end of each lever 16 is a finger 19 having the lower end thereof rabbeted to form a shoulder 20, while connected to the upper end of such finger is one extremity of a coiled compression spring 21, the free end of the latter engaging the lug 18 on the particular lever 16. When each lever 16 is in its raised or elevated position, the shoulder 20 engages the adjacent end of the plate 13 and so holds the lever up.

Extending upwardly from the bottom wall of the casing 1 in advance of the bearing block 7 is a vertical plate 22 and secured to the opposite side edges of such plate are the vertically disposed portions of angle arms 23 having the horizontal parts thereof extended rearwardly of the vertical plate and suitably spaced apart and formed with alining apertures to receive a rod 24 disposed in a horizontal plane above the fingers carried by the levers 16. To the rear end of each lever 16 is fastened one extremity of a contractile spring 25 having the free terminal thereof coiled about the rod 24 and thence extended downwardly to form a resilient spring finger 26. Depending from the rod 24 and mounted for swinging movement thereon are small rectangular plates 27 each disposed in advance of one of the fingers 19 and adapted, when the particular lever is held in elevated position, to contact with the adjacent part of the finger 19 and, when actuated, swing the latter about the pivotal connection with the lever against the action of the spring 21 whereby the shoulder 20 will be disengaged from the plate 13 and the lever swung downwardly under the action of the contractile spring 25. The inner side edge of each lever 16 at a point immediately in advance of the lug 18 is notched or cut out as at 28 to provide a downwardly inclined wall 29, while slidably mounted upon a guide 30 adjacent the inner side edge of each lever 16 is a bar 31 equipped with a laterally extending lug 32 provided with an inclined wall 33 and fitting within the notch or cut out portion 28 of the respective lever, the inclined wall 33 of the lug contacting with the inclined wall 29 of the cut out portion and is adapted, when the sliding bar 31 is moved inwardly to engage the inclined wall of such cut out portion of the lever and so force the latter upwardly against the action of the respective contractile spring 25 thereby enabling the shoulder 20 on the respective finger to engage the upper surface of the plate 13 and so hold the respective lever elevated. These sliding bars 31 are normally held retracted or in an inactive position so that when the levers are relieved of the influence

of the latching fingers such levers may be thrown downwardly under the action of the contractile spring 25. In the present instance, each sliding bar 31 has connected thereto one terminal of a coiled contractile spring 34, the opposite end of such spring being fastened to the vertical plate 22.

Suitably fastened to the lower wall of the casing 1 immediately adjacent to the front wall of such casing is a rectangular guide strip 35 formed with an elongated longitudinal slot 36 having the opposite walls thereof formed with alining apertures 37 registering with apertures 38 in the front wall of the casing.

Slidably mounted within the sets of alining apertures 37, 38 at the opposite sides of the center set of such apertures are plungers 39, 39 each having the free end thereof passed through an aperture in the vertical plate 22 and terminating in advance of one of the swinging plates 27, while slidably mounted within the sets of apertures 37, 38 adjacent to the plungers 39, 39 and at the outer sides thereof are plungers 40, 40 each having the shank thereof passed through an aperture in the vertical plate 22 and the free end thereof in contact with a stem 41 on one of the sliding bars 31, the stems of the bars being slidably disposed within apertures in a strip 42 carried by the forward end of the plate 13 projecting upwardly therefrom. In the set of apertures 37, 38 between the plungers 39, 39 is slidably mounted a plunger 41' having the shank thereof connected to the collar 5 carrying the bridging strip 10, the plungers 39, 39, 40, 40 and 41' being encircled by coiled expansion springs 43 disposed between the walls of the elongated slot 36 in the guide strip 35, one end of each spring contacting with the inner wall of the slot, while the opposite end thereof bears against a pin or the like carried by the plunger shank, such springs acting to hold the plungers normally inactive.

From this construction, it will be obvious that by depressing the plunger 41', the bridging strip 10 will be moved inwardly to bridge the contact strips 9, 9, while through the medium of the plungers 40, 40, the sliding bars 31 may be moved inwardly along the upper face of the plate 13 so that the inclined walls of the lugs carried by such bars will engage the similar walls of the cut out portions in the levers and so elevate the latter against the action of the contractile springs 25 whereby the shoulders 20 on the fingers 19 will engage the upper surface of the plate 13 and so hold the levers elevated. Should it be desired to render the bridging strip 10 immovable under the action of the plunger 41' so far as bridging the contacts is concerned, the plungers 39, 39 may be moved inwardly to swing the

plates 27 into engagement with the adjacent ends of the fingers 19 whereby the latter will be swung about their pivotal connections with the levers 16 and against the action of the spring 21 thereby disengaging the shoulders on the fingers from the plate 13 and enabling the contractile springs 25 to function to swing the levers 16 to lowered position thereby disposing the lower extremities of the fingers 19 in the path of movement of the bridging strip 10 and between such bridging strip and the contact strips 9. Thus, it will be impossible for one unacquainted with the structure of the switch or the combination of the plungers to manipulate the bridging strip 10 in order to bridge the contact strips 9.

The contact strips 9, 9 and the bridging strip 10 constitute what we term the secondary contacts of the switch and in conjunction with such set of secondary contacts we employ a set of primary contacts, composed in the present instance, of two pairs of contacts, the contacts of each pair embodying a resilient contact 44 suitably fastened to a binding post 45 upstanding from the lower wall of the casing 1 adjacent to the opposite side of the vertical plate 22, and a contact strip 46 fulcrumed as at 47 for swinging movement and adapted to engage the resilient contact 44. Each swinging contact strip 46 is disposed in the path of movement of a lever 48 fulcrumed between its ends as at 49 upon the lower wall of the casing 1 and having one end thereof contacted by one terminal of an expansion spring 49', the free terminal of the latter being secured to a block 50 uprising from the lower wall of the casing adjacent to the lever 48. Arranged at substantially right angles to each lever 48 and fulcrumed between its ends adjacent to one side of the block 2 is a lever 51 having the rear face thereof equipped with a lug 52 spaced apart therefrom and adapted to be engaged by a lug 53 on the inner end of the lever 48, contractile springs 54 each having one end thereof fastened to the respective lever 51 and the opposite end secured to the lower wall of the casing or housing 1 as at 55.

The levers 51, 51 act in the capacity of a combined lock and obstructing device and for this purpose have their extremities disposed adjacent to the bridging strip 10 in turned to form lugs 56 adapted, under certain conditions, to enter the space between the contact strips 9, 9 and the bridging strip 10 and so prevent bridging of the strips 9, 9 and under other conditions to engage the extremities of the bridging strip 10 and hold the latter in contact with the contact strips 9, 9 against the action of the spring 6. In the open position of the pairs of contacts constituting the primary set, the lugs 56 on the respective ends of the levers 51, 51 are

disposed beyond the adjacent end edges of the bridging strips 10, while the locking lugs 53 on the respective ends of the levers 48 interlock with the lugs 52 on the lever 51 and are held in such interlocking engagement by means of the expansion springs 49, thereby holding the swinging contact strips 46 of the set of primary contacts out of engagement with the yielding contacts 44 of such set, the contractile springs 54 being under tension in this position of the parts.

In order to release the levers 48 from the influence of the locking lugs 53 and 52 and swing such levers against the tension of the respective springs 49 so that the set of primary contacts may be actuated to circuit closing position, we mount in the outer sets of registering apertures 37 and 38 plungers 57, 57 having the free extremities of the shanks thereof adapted to contact with the outer extremities of the levers 48, 48. Assuming the parts to be in the positions illustrated in Fig. 4 wherein the primary set of contacts are shown to be open, and it is desired to close such set of contacts, the plungers 57, 57 are forced inwardly thereby swinging the levers 48 about their pivots 49' and against the tension of the spring 49 and so disengaging the locking lugs 53 on the respective ends of such levers from engagement with the lugs 52 on the levers 51. In the continued movement of the plunger 57, 57, the swinging contacts 46 of the primary set move into engagement with the yielding contacts 44 under the action of the levers 48, while the springs 54 react to throw the ends of the lugs 52 on the levers 51 into the path of movement of the lugs 53 on the levers 48 thereby preventing the last-mentioned levers from returning to inactive positions under the influence of the expansion springs 49'. If the switch is being manipulated by one acquainted with the combination and such person desires to close the circuit controlled by the switch, the plunger 41' is pressed inwardly so that the bridging strip 10 will bridge the contact strips 9, 9 previous to the release of the levers 51 just described so that the lugs 56, 56 on the respective ends of such levers will engage the bridging strip 10 and hold the latter in circuit closing position. It will be seen that if one unacquainted with the manipulation of the switch should depress one or the other of the plungers 17, the respective lever 51 would be unlocked and the lug 56 thereon thrown into the path of movement of the bridging strip 10 thereby rendering the switch inoperative so far as closing the circuit controlled thereby is concerned.

In order that the levers 51, 51 may be restored to inactive position, subsequent to the releasing of the same under the action of the plungers 57, 57, any suitable means may be employed. In the present instance, a releas-

ing bar 58 is slidably disposed within the casing 1 in suitable guides at the rear of the free extremities of the levers 51, 51 and has one end thereof projecting outwardly of one side of the casing. Formed on the releasing rod 58 adjacent to one of the levers 51 is the lug 59 adapted to engage such lever and swing the same about its pivot against the action of the spring 54, while pivotally mounted upon the lower wall of the casing as at 60 adjacent to the other lever 51 is an arm 61 having one end thereof disposed in the path of movement of the releasing rod 58, a contractile spring 62 normally holding one end of the arm 61 out of contact with the adjacent portion of the lever 51. Thus, it will be seen that when the releasing rod 58 is moved inwardly of the casing, the lug 59 thereon will engage the adjacent lever 51, while the free end of such rod will contact with the arm 61 and so swing the latter about its pivot point 60, thereby swinging both levers 51, 51 against the tension of the springs 54 so as to restore such levers to inactive position whereby the springs 49' will react to swing the levers 48 and so throw the lugs 53 into locking engagement with the lugs 52 thereby opening the switch as clearly illustrated in Fig. 4 of the drawings.

The primary and secondary sets of contacts are connected in series in an electric circuit so that it will be impossible to energize the circuit without closing both sets of contacts. This circuit includes a suitable source of electrical energy such, for instance, as a dynamo 63, a conductor 64 leading from one side of the generator and terminally connected to one of the swinging contacts 46 of the primary set, a wire 65 leading from the yielding contact 44 co-operating with the just mentioned swinging contact and forming a continuation of the conductor 64, the free terminal of the wire 65 being tapped onto the other yielding contact of the primary set. From the swinging contact strip 46 co-operating with the last-mentioned yielding contact 44 of the primary set leads a wire 66 forming, with the wire 65, a continuation of the conductor 64 and including suitable translating devices. The free terminal of the wire 66 is tapped onto one of the contact strips 9, while to the remaining contact strip 9 is fastened one terminal of a conductor 67 leading back to the generator and tapped onto the opposite side thereof.

From the foregoing description taken in connection with the accompanying drawings, the construction, mode of operation and manner of employing our electric circuit controlling switch will be readily apparent. It will be seen that we have provided a combination switch for the control of electric circuits whereby the circuit can

not be closed unless both sets of contacts have been properly manipulated. Furthermore, it will be observed that the levers 51, 51 act to lock the primary set of contacts in circuit closing position and the secondary set of contacts in circuit closing position when the switch is manipulated by one acquainted with the combination; but when operated by an unauthorized person it will be seen that the lugs 56, 56 on the respective ends of the levers 51, 51, assuming of course, that the plungers 57, 57 have been depressed, previous to the actuation of the plunger 41', will enter the space between the contact strips 9, 9 and the bridging strip 10 thereby obviating the closing of the circuit, the levers 51, 51 performing the two-fold function of a lock for both sets of contacts and of an obstructing device for the bridging strips.

While we have herein shown and described one preferred form of our invention by way of illustration, we desire to have it understood that we do not limit or confine ourselves to the precise details of construction herein described and delineated, as modification and variation may be made within the scope of the claims and without departing from the spirit of the invention.

We claim:

1. In an electric circuit controlling switch, a set of contacts connected in the circuit, a bridging strip movable into engagement with said contacts, a second set of contacts connected in series with the first contacts and normally out of engagement with each other, means for moving said bridging strip into engagement with the co-operating contacts, means for engaging the second-named contacts with each other, and means common to said bridging strip and said second-named contacts to lock the bridging strip in engagement with the companion contacts and the movable contacts in engagement with each other.

2. In an electric circuit controlling switch, a set of contacts connected in the circuit, a bridging strip movable into engagement with said contacts, a second set of contacts connected in series with the first contacts and normally out of engagement with each other, means for moving said bridging strip into engagement with the co-operating contacts, means for engaging the second-named contacts with each other, means common to said bridging strip and said second-named contacts to lock the bridging strip in engagement with the companion contacts and the movable contacts in engagement with each other, and manually operable means for releasing said locking means whereby the bridging strip may be disengaged from the companion contacts and the second-named contacts disengaged from each other simultaneously.

3. In an electric circuit controlling switch, a set of contacts connected in the circuit, a bridging strip movable into engagement with said contacts, a second set of contacts connected in series with the first contacts and normally out of engagement with each other, means for moving said bridging strip into engagement with the coöperating contacts, means for engaging the second-named contacts with each other, means common to said bridging strip and said second-named contacts to lock the bridging strip in engagement with the companion contacts and the movable contacts in engagement with each other, manually operable means for releasing said locking means whereby the bridging strip may be disengaged from the companion contacts and the second-mentioned contacts disengaged from each other simultaneously, and means for throwing the bridging strip out of engagement with the coacting contacts upon the operation of said releasing means.
4. In an electric circuit controlling switch, a pair of contacts connected in the circuit, a bridging strip adapted to bridge said contacts, a second set of contacts connected in series with the first contacts and normally spaced apart, means for moving said bridging strip into engagement with the coöperating contacts, means for actuating one of the last-mentioned contacts into engagement with the remaining contact, and means common to said bridging strip and said last-mentioned contacts to lock the bridging strip in engagement with the coöperating contacts and the last-mentioned contacts in engagement with each other simultaneously.
5. An electric circuit controlling switch comprising a pair of contacts, a bridging strip adapted to bridge said contacts, a second set of contacts connected in series with the first-mentioned contacts and normally out of engagement with each other, means for moving said bridging strip into engagement with the companion contacts, means for moving one of the last-mentioned contacts into engagement with the remaining contact, and means under the control of said last means and movable into the path of said bridging strip to hold the latter out of engagement with the coöperating contacts, and means movable into the path of said bridging strip independently of said last means to hold the bridging strip out of engagement with the coöperating contacts.
- for moving one of the last-mentioned contacts into engagement with the remaining contact, and means movable into the path of said bridging strip to hold the latter out of engagement with the coöperating contacts.
6. An electric circuit controlling switch comprising a pair of contacts, a bridging strip adapted to bridge said contacts, a second set of contacts connected in series with the first-mentioned contacts and normally out of engagement with each other, means for moving said bridging strip into engagement with the companion contacts, means for moving one of the last-mentioned contacts into engagement with the remaining contact, and means under the control of said last means and movable into the path of said bridging strip to hold the latter out of engagement with the coöperating contacts.
7. An electric circuit controlling switch comprising a pair of contacts, a bridging strip adapted to bridge said contacts, a second set of contacts connected in series with the first-mentioned contacts and normally out of engagement with each other, means for moving said bridging strip into engagement with the companion contacts, means for moving one of the last-mentioned contacts into engagement with the remaining contact, and means under the control of said last means and movable into the path of said bridging strip to hold the latter out of engagement with the coöperating contacts, and means movable into the path of said bridging strip independently of said last means to hold the bridging strip out of engagement with the coöperating contacts.
- In testimony whereof we affix our signatures in presence of two witnesses.
